(57) **CLAIM**

The ornamental design for an electronic hand controlled computer input device having multiple hand movement sensors and a LCD display, as shown and described.

DESCRIPTION

FIG. 1 is a back view showing my design of an electronic hand controlled computer input device having multiple hand movement sensors and a LCD display;

FIG. 2 is a bottom view thereof;

FIG. 3 is a front view thereof;

FIG. 4 is a left side thereof;

FIG. 5 is a right side thereof;

FIG. 6 is a top view thereof;

FIG. 7 is a perspective top view thereof; and,

FIG. 8 is a perspective bottom view thereof.
